UNITED STATES PATENT OFFICE.

JEREMIAH M. WATSON, OF BOSTON, MASSACHUSETTS.

MACHINE FOR CUTTING LEATHER-BOARD.

SPECIFICATION forming part of Letters Patent No. 506,573, dated October 10, 1893.

Application filed January 23, 1891. Serial No. 378,766. (No model.)

To all whom it may concern:

Be it known that I, JEREMIAH M. WATSON, of Boston, county of Suffolk, State of Massachusetts, have invented an Improvement in Machines for Cutting Leather-Board and the Like, of which the following description, in connection with the accompanying drawings, is a specification, like letters on the drawings representing like parts.

10 This invention relates to machines for cutting sheets of leather board and the like into strips, and for chamfering the longitudinal edges of said strips, the object of the invention being to provide a machine, in which the 15 leather board, whatever be its variable thickness, shall be automatically presented to the cutting knife always in the same position relative thereto, whereby the strips cut are necessarily of uniform width. To obtain such 20 a result in accordance with this invention I provide two centering devices which act upon the sheet of board or stock upon opposite sides to hold the same in proper adjusted position with relation to the knife. These centering devices are preferably in the form of 25 presser feet used in connection with suitable feed rolls, which feed the stock between the presser-feet to the knife, suitable means being provided whereby the presser-feet, when 30 moved to accommodate thicker or thinner sheets, are moved simultaneously in opposite directions, in order that the horizontal central line of the board or stock, whatever be the thickness of the latter, will always re- 35 main in the same relative position to the knife, thereby assuring uniformity in the width of the strips cut, any variations in the thickness of the board or stock being pro- 40 vided for by an equal movement of the presser- feet. The knife is preferably formed with a 45 diagonal cutting edge, in order that it may be held in its support in a diagonal position with relation to the shaft carrying the feed-rolls, and yet present a cutting edge parallel to said 50 shaft, although it may be arranged at a slight angle to insure a draw-cut if desired. The knife is also slightly turned on its axis to present a cutting edge standing at an angle with relation to the axis of rotation of said shafts 55 to thereby cross diagonally the path of movement of the stock, and sever the same upon a diagonal line to thereby produce strips both

longitudinal edges of which are chamfered, but at opposite sides.

Figure 1 shows in side elevation a machine 55 for stripping and chamfering leather board and the like embodying this invention. Fig. 2, shows in front elevation the machine shown in Fig. 1, the table being removed; Fig. 3, a top view of a portion of the knife; Fig. 4, a 60 sectional detail of the knife and its support; Figs. 5 and 6, sectional details of the adjustable bearings for the shafts; Fig. 7, a detail showing the strips as cut and chamfered.

In the machine herein shown to illustrate 65 this invention the centering devices constitute presser feet used in connection with feed rolls. The main drive shaft a , having on it suitable driving pulleys, carries a pinion a' , which in turn drives a toothed drive wheel a^3 70 fixed to a shaft a^3 . A pinion a^4 is secured to the shaft a^3 which engages with a toothed wheel a^5 secured to a shaft a^6 arranged parallel to the shaft a^3 . By this driving mechanism the shafts a^3 , a^6 will be rotated in opposite directions. The shaft a^3 has fixed to it two feed-rolls b , b' , located a short distance apart, and the shaft a^6 has fixed to it two feed-rolls b^2 , b^3 , also located a short distance apart, and which are made to co-operate with the feed-rolls b , b' , 80 to feed the stock forward. The shafts a^3 , a^6 , have their bearings at their ends adjacent the pinions in bearing blocks n , n' , each having a cylindrical stud n^2 see Fig. 6 seated in the frame-work, said bearings being held in place 85 by nuts n^3 . These bearings can therefore turn, the studs n^2 serving as pivots. The shafts a^3 , a^6 have their bearings, at or near their forward ends, in boxes a^7 , a^8 , which are bolted to blocks a^9 , see Fig. 5, adapted to fit 90 and slide in guide-ways a^{9x} in the frame-work A. The boxes a^7 , a^8 are supported in a yielding manner, each by similar mechanism, so that only one will be described. A lug c , see Fig. 2, projecting from the frame-work, 95 has a hole through it, into which a screw c' is fitted, which screw also has a hole through it and a rod c^2 is extended through the hole in the screw c' , and is screwed into or otherwise secured to a box a^7 or a^8 , said rod having 100 at its opposite end suitable check nuts c^3 . A spring c^4 surrounds the rod c^2 , one end of which bears against the end of the screw c' , and the other end against the box, the ten-

deney of which spring is to distend and press one box in a direction toward the opposite box. The yielding springs for the boxes act to press the feed-rolls b, b' and b^2, b^3 together, 5 permitting them to yield however for any variation in the thickness of stock. Two presser-feet d, d' which constitute the centering devices are supported vertically in the framework, one above the other, and adapted to bear 10 on opposite sides of the stock, which is fed forward between them. The presser-foot d^2 has a pin 2, to which a spring 3 is secured, the opposite end of said spring being attached to a fixed point, as to the stud 4 on the frame. 15 This spring 3 normally acts to keep the presser-foot d in its elevated position, in which position its shank bears against an adjusting screw e which passes down through a cross-bar e' pivoted at e^2 , the opposite end 20 of said cross-bar e' bearing upon a strong spring e^3 which is seated in a cup, not shown, contained in a socket in a stationary lug e^6 , said cup being supported by an adjusting screw e^7 . An arm f is formed integral with 25 or secured to the cross-bar e' , said arm f being bifurcated at its outer end to engage a stud f' on the upper end of an arm f^2 which is secured to and formed integral with the cross-bar f^4 pivoted at f^8 . The cross bar e' 30 and its arm f , and the cross bar f^4 and its arm f^2 , constitute in effect two bell-crank levers, by which name they will be hereinafter designated in the claims. The cross-bar f^4 is like the cross-bar e' and bears at one end 35 upon a strong spring f^6 which is seated in a cup f^6 fitted in a socket f^7 formed in the under side of a stationary lug f^8 ; and at its opposite end bears against an adjusting screw f^9 upon which the presser-foot d' rests by 40 gravity. By means of the adjusting screws e, f^9 the cross-bar e' and arm f , and the cross-bar f^4 , and arm f^2 , act as bell-crank levers, one moving the other. By means of this mechanism connecting the presser-feet d, d' 45 one with the other, it will be seen that whenever one is moved the other will be correspondingly moved. Curved guides 10, 12 are secured to the frame-work which assist in feeding the stock to the feed-rolls. A knife 50 k is located just back of the presser-feet d, d' and feed-rolls, said knife being formed as a flat blade, the shank of which is held between clamps k', k' , which are semi-circular in cross-section, as represented in Figs. 1 and 4, and 55 adapted to fit the circular opening in the support k^2 secured to the frame-work of the machine. The blade k has a diagonal cutting edge k^3 , see Fig. 3, and the support k^2 is adapted to hold the blade diagonally with relation to the shafts a^3, a^6 , as shown by dotted lines Fig. 2, so that the cutting edge k^3 60 will lie substantially parallel to said shafts. The circular clamp k', k' is held in position in its support by a set screw k^4 , and said clamp 65 is turned so that the blade is inclined to diagonally cross the path of movement of the stock passing between the feed-rolls to there-

by cut the stock from side to side diagonally, as represented in Fig. 2. By means of the circular clamp k', k' , and set screw k^4 , the 70 blade k may be tipped more or less, as desired, and even placed in truly vertical position to cut the stock at right angles. The stock thus cut is chamfered on each side, but at opposite edges, as represented in Fig. 7. 75

I do not desire to limit myself to the particular construction of mechanism herein shown for connecting the centering devices or presser-feet d, d' , as other mechanism may be employed, by which the same may be moved simultaneously, or one may move the other. 80

I claim—

1. In a machine for cutting leather board and the like into strips, the combination with a knife, of yielding centering devices to act 85 upon opposite sides of the stock fed to the knife, and connecting mechanism whereby said centering devices are moved simultaneously in opposite directions to accommodate stock of varying thicknesses and hold the 90 stock always in a central position with relation to said knife whatever be the thickness of the stock, substantially as described.

2. In a machine for cutting leather-board and the like into strips, feed-rolls, and means 95 to rotate the same, combined with centering devices to act upon opposite sides of the stock, and means whereby said centering devices are moved simultaneously in opposite directions to accommodate stock of varying 100 thicknesses, and the knife, substantially as described.

3. In a machine for cutting leather-board and the like, feed rolls, and means to rotate the same, combined with centering devices 105 to act upon opposite sides of the stock, and means to provide an equal simultaneous movement of the centering devices in opposite directions toward and from the central point, combined with a diagonally positioned knife 110 arranged opposite the central point between said centering devices, whereby stock of varying thicknesses is always fed to said knife in the same central or relative position, substantially as described. 115

4. In a machine for cutting leather-board and the like, feed rolls, combined with two centering devices which bear on opposite sides of the stock, and connecting mechanism whereby one centering device is moved by and simultaneously with the other, and a knife, substantially as described. 120

5. In a machine for cutting leather-board and the like, feed rolls, and means to rotate the same, combined with two centering devices to act on opposite sides of the stock and means whereby said centering devices are moved simultaneously in opposite directions, and adjusting devices to vary the separation of said centering devices one from the other, 130 and a knife, substantially as described.

6. In a machine for cutting leather-board and the like, two centering devices to act at opposite sides upon the stock, mechanism where-

by said centering devices are moved simultaneously in opposite directions to accommodate varying thicknesses of stock, and hold the latter always in the same central position, 5 combined with feed rolls made yielding to adapt themselves to the varying thicknesses of stock without moving the same from its central position as held by the centering devices, and a knife having its cutting edge arranged 10 or presented diagonally across the path of movement of the stock, substantially as described.

7. In a machine for cutting leather-board and the like, feed rolls, and means to rotate 15 the same, combined with two centering devices and connecting mechanism consisting of two bell-crank levers connected at one of their ends with the said centering devices, and at their opposite adjacent ends with each 20 other whereby movement of one centering

device causes like opposite movement of the other, and a knife, substantially as described.

8. In a machine for cutting leather board and the like, the combination with four yielding feed-rolls, arranged in pairs the rolls of 25 each pair facing each other, and means to rotate the same, of centering devices arranged between the two pairs of rolls and to act upon opposite sides of the stock, and means whereby said centering devices are moved simultaneously in opposite directions to accommodate stock of varying thicknesses, and a knife, 30 substantially as described.

In testimony whereof I have signed my name to this specification in the presence of 35 two subscribing witnesses.

JEREMIAH M. WATSON.
